AUTOMATIC FIRE ALARM CASE

Raymond W. Ostrander, Los Angeles, Calif.
Application August 12, 1954, Serial No. 31,846

Term of patent 3½ years

(Cl. D72—1)

Fig. 1.

Fig. 2.

Fig. 3.

To all whom it may concern:

Be it known that I, Raymond W. Ostrander, have invented a new, original, and ornamental Design for an Automatic Fire Alarm Case, of which the following is a specification, reference being had to the accompanying drawing, forming a part hereof.

Fig. 1 is a perspective view of an automatic fire alarm case showing my new design;

Fig. 2 is a side elevational view thereof; and
Fig. 3 is a bottom plan view.

I claim:

The ornamental design for an automatic fire alarm case, as shown.
